UNITED STATES PATENT OFFICE.

VALÉRIE D. OHRENSTEIN, OF ELMHURST, ILLINOIS.

INFANT'S GARMENT.

1,394,213.

Specification of Letters Patent.

Patented Oct. 18, 1921.

Application filed April 30, 1921. Serial No. 465,739.

To all whom it may concern:

Be it known that I, VALÉRIE D. OHRENSTEIN, a citizen of the United States, residing at the village of Elmhurst, in the county 5 of Du Page and State of Illinois, have invented a new and useful Improvement in Infants' Garments, of which the following is a specification.

My invention relates to certain new and 10 useful improvements in garments for infant-wear, of the type for covering the entire body, and it is fully described and explained in the specification and shown in the accompanying drawings, in which—

15 Figure 1 is a view in front elevation of my improved garment in its normally closed condition when worn, and Fig. 2 is a similar view of the same in opened condition for exposure of and access to the lower part of the 20 body of the wearer.

The primary object of my invention is to provide a construction of garment in the class referred to whereby it may be readily and conveniently opened for exposure of 25 and access to the lower part of the wearer's body, as for diaper application and changing, without requiring, to accomplish the opening purpose, that the portion of the garment covering the upper part of the body 30 be disturbed or opened with resultant exposure of such upper part.

The garment comprises a front section 3 and a corresponding rear section 4, these sections being each formed with arm-exten- 35 sions sewed together along their edges, to form the arms 5, 5 at opposite sides of a neck-opening 6. The edges of the sections 3 and 4 below the arms are stitched together to the points indicated at x , x , from which 40 similar flaps 7, 7 of trapezoidal form extend from the rear section, which also has a lower flap-extension 8 to fold upwardly against the lower portion of the face of the section 3, the flaps 7 being adapted to fold toward 45 each other over the folded flap 8, as represented in Fig. 1.

A breast-opening is shown in the garment at 9 with buttons 10 on one side and a closure-flap 11 on the other side having but- 50 ton-holes to engage the buttons 10.

The flap 8 contains a button-hole at 12^a and button-holes at 13^a to respectively engage, in its folded condition, a button at 12 and buttons at 13 on the section 3; and but- 55 ton-holes at 13^b on the flaps 7 are adapted,

when these flaps are folded toward each other, in the mutually overlapping condition represented in Fig. 1, over the folded flap 8 to engage the button 12 for fastening them.

Should the garment become unbuttoned 60 at the buttons 13, 13, or should said buttons be detached the flap portion 8 would protect the wearer from exposure due to its being buttoned at 12, the flaps 7 extending there- over and also secured to the button 12 by 65 means of the buttonholes 13^b as clearly illus- trated in the drawing, thus giving additional security from exposure and providing a single securing point or means for said flaps 7 and 8. It is obvious that, if desired, the but- 70 tons 13, 13, may be omitted, the securing means 12 serving to effectually hold the parts in closed position.

My improvement enables the lower part 75 of the body of an infant wearer of the gar- ment to be completely uncovered, on unbut- toning the flaps and spreading them out into the condition represented in Fig. 2, for ex- posure with convenient access for attention 80 to the infant's toilet without requiring the 85 garment to be otherwise disturbed with in- cidental uncovering of the upper part of the wearer's body and resultant liability to chilling; and with the flaps folded into the condition represented in Fig. 1 they afford 90 complete protection in the way of sealing the garment.

I realize that considerable variation is 95 possible in the details of the construction herein shown and described, and I do not in- tend to limit myself thereto except as pointed out in the following claims, in which it is my intention to claim all the novelty inher- ent in my improvement as broadly as is 100 permitted by the state of the art.

I claim:

1. A garment of the character described comprising a rear and a front section, the rear section having a lower flap-extension folding over the lower portion of the front section, flaps extending from the opposite sides of the garment and folding toward each other over said folded flap-extension, and means adjacent the lower end of said front section for securing said flap-extension 105 and said side flaps in place at one point on the garment and in superposed relation.

2. A garment of the character described, having a permanently closed front section and a rear section, said sections being free 110

along the lower portions of the sides of the garment, the rear section having a lower flap-extension folding upwardly over the lower portion of the front section and containing button-holes, button-hole-containing flaps of trapezoidal form extending from the opposite free side-portions of the rear sec-

tion and folding toward each other over said folded flap-extension, and buttons on said front section engageable by said button-holes in the folded positions of said flap-extension and flaps. 10

VALÉRIE D. OHRENSTEIN.
